SAMUEL A. NEUHARD, OF MILTON, PENNSYLVANIA, ASSIGNOR OF ONE-THIRD TO WILLIAM J. CALDWELL AND ONE-THIRD TO HARRY W. CHAMBERLIN, BOTH OF MILTON, PENNSYLVANIA.

RAILROAD-RAIL JOINT.

No. 855,725.

Specification of Letters Patent.

Patented June 4, 1907.

Application filed February 16, 1907. Serial No. 857,701.

To all whom it may concern:

Be it known that I, SAMUEL A. NEUHARD, a citizen of the United States, residing at Milton, in the county of Northumberland and State of Pennsylvania, have invented a new and useful Railroad-Rail Joint, of which the following is a specification.

This invention relates to certain improvements in a rail joint by means of which the abutting ends of railway rails can be so joined as to produce a substantially continuous tread, yet leaving sufficient space between the end for expansion. These objects are accomplished by matching the ends of each rail so that when two rails are brought together end to end, their ends will overlap and interlock in such a way that an approximated continuous rail is provided having all the strength and weight supporting qualifications necessary to uphold passing trains without yielding under the strain.

To clearly illustrate the invention and more clearly elucidate the following description and appended claims, attention is called to the accompanying drawings, in which

Figure 1 is a perspective view of the approximate ends of two rails separated, provided with the joint. Fig. 2 is a plan view of two rails joined. Fig. 3 is a side elevation on a reduced scale of two separate rails viewed from the side opposite that shown in Fig. 1. Fig. 4 is a vertical sectional view on the line 4—4. Fig. 5 is a vertical sectional view on the line 5—5.

Like characters of reference indicate corresponding parts throughout the drawings.

The numerals 1 and 2 indicate the adjoining ends of two rails, 3, 4 the fish plates on either side and 5 the bolts for joining the rails and fish plates, the latter and the bolts being of the usual construction.

In applying this invention to rails of well known section in which each has a head 6, web 7 and base 8, one end of each rail is shaped as at A, shown on the end of rail 1, while the other end of the rail is fashioned as at B on the end of rail 2.

Referring first to the shape of the rail end at A, it is to be noted that one half of said end (here shown on the right side) has been removed by a central vertical cut extending back from the end a suitable distance to a point say 9 where it is met by a transverse

cut, leaving two vertical faces 10 and 11 on the rail end at a right angle to each other. 55 The outer edge of the base flanges 12, on the same side, is also cut away for a short distance back of the face 11 to a point say 13, where a transverse cut is made leaving a width of flange 14 equal to the overhanging 60 of the rail head 6. A portion of the base flange 15 on the opposite side of the rail is also removed, but in this case that part cut away extends from the end of the rail to a cut 13^a in line with the cut 13 leaving a narrow flange 16, the combined width of the two narrow flanges 14 and 16 being substantially the same as the width of the head 6, this width, however, may be increased or diminished as circumstances demand. A 70 portion of the base 8 extending from the end of the rail back to the points 13, 13^a is undercut leaving a shoulder 17^a for a purpose to be explained hereinafter.

The end B on the opposite end of each rail 75 is treated in a different manner from the end A. Here the vertical central cut extends through the head 6 and web 7 but only a small portion of the upper part of the base 8 for a distance back from the end of the rail 80 equal to the distance from the shoulder 17^a to the end A of the rail. One half of the divided end is removed in such a manner as to leave a channel 18 of a width equal to and on the same side of the rail as the narrow flange 85 16. The remaining half 19 of the end B is left with vertical faces 20 and 21 similar to and corresponding both in size and shape to the respective faces 10 and 11 on the rail end A. The section 19 of the end B is cut back 90 from the end sufficiently to admit that portion of the end A between the vertical face 11 and the point 13, and the channel 18 widened to receive the narrow flange 14.

In laying the rails, they are placed on the 95 cross tie with the end A of all the rails pointing in the same direction. As they are brought together end to end, the end A of rail 1 will be placed on the end B of rail 2 the narrow flange 16 resting in the channel 18. 100 The loose rail being then moved endwise, the faces 10 and 20 of the reduced portions 19 and 19^a will be brought into contact and the ends of said reduced portions seat themselves against the respective faces 9 and 21. 105 The undercut portion 17 will slide on the bot-

tom of the channel 18 as will also the narrow flange 14. The ends being now in position they are securely fastened by the fish plates and bolts in the usual manner. The operation of uniting the ends of the rails may be varied if desired, for instance the rail end B may be slid under the end A, or the rail 1 may be lifted bodily and the end A placed in the seat in end B.

10. What I claim is:—

1. In a railway rail joint, the combination of two rails each having a lateral half of its head and web and the base flange of one rail at their adjoining ends removed to permit 15 said ends to overlap, the base flange at the end of one of said rails being channeled to admit the reduced flange on the end of the other rail.

2. In a railway rail joint the combination 20 of two rails each having a lateral half of its head and web and the base flange of one rail at their adjoining ends removed to permit said ends to overlap and fit against each

other, the rail which has one half its base flange removed having also a portion of the 25 bottom and edge of the remaining half of the flange cut away to fit a channel formed in the base flange of the other rail.

3. In a railway rail joint, the combination of two rails each having a lateral half of its 30 head and web at their adjoining ends removed, the base flange of one rail projecting beyond the end of the head and web and channeled, the base flange of the other rail being cut away on one side, and partly removed on the other side and bottom to adapt it to fit the channel in the first mentioned rail.

In testimony that I claim the foregoing as my own, I have hereto affixed my signature in the presence of two witnesses.

SAMUEL A. NEUHARD.
